(57) **CLAIM**

The ornamental design for a ceiling fan motor housing, as shown and described.

DESCRIPTION

FIG. 1 is a top perspective view of a motor housing of the ceiling fan motor housing according to an embodiment of the invention;

FIG. 2 is a bottom perspective view of the ceiling fan motor housing of FIG. 1;

FIG. 3 is a side view of the ceiling fan motor housing of FIG. 1;

FIG. 4 is a bottom view of the ceiling fan motor housing of FIG. 1; and,

FIG. 5 is a top view of the ceiling fan motor housing of FIG. 1.

The broken lines immediately adjacent the shaded areas depict the bounds of the claimed design, while all other broken lines are directed to environment.

1 Claim, 5 Drawing Sheets(56)
